UNITED STATES PATENT OFFICE.

KARL GAMMEL, OF STUTTGART, GERMANY.

DRYING MACARONI.

No. 918,496.

Specification of Letters Patent. Patented April 13, 1909.

Application filed December 13, 1907. Serial No. 406,300.

To all whom it may concern:

Be it known that I, KARL GAMMEL, a citizen of the German Empire, residing at Stuttgart, Würtemberg, Germany, have invented 5 certain new and useful Improvements in Drying Macaroni and the Like; and I do hereby declare the following to be a full, clear, and exact description of the invention, such as will enable others skilled in the art to 10 which it appertains to make and use the same.

This invention has for its object improvements in spreading out and drying macaroni and the like.

15 In the ordinary methods the threads of paste emerging in large numbers from the press were hitherto caught in wood boxes, cut therein to the desired lengths, and these wood boxes conveyed with the macaroni to 20 the drying rooms. The macaroni also was laid in several superincumbent layers and was covered with a light cushion. In order to dry the macaroni an air current was then passed through the macaroni pipes themselves and if possible through the small intervals formed by the layering. The drying 25 process thus only commenced with the air being blown through, for which of course a considerable expenditure of power is necessary owing to the small section of the pipes. Now it is evident that the drying in this manner, particularly of thin macaroni with or without very small holes, was not at all uniform and thorough, and therefore the goods 30 were frequently spoiled.

35 By other processes the macaroni is conveyed by suitable devices onto pasteboard or cardboard supports or trays, or spread on these by hand, after which these pasteboard supports or trays are laid in hurdles or stages, covered with several sheets of paper, and then brought into drying chambers, this drying process, which is itself a slow one, being accelerated, if necessary, by means of more 40 or less artificial ventilation. The macaroni in the hurdles or stages must be very carefully covered with sheets of paper in order to avoid any cracking of the goods, because the air in these drying chambers is usually very 45 dry, and also the space required for arranging the hurdles in this drying process is very great.

50 The method according to this invention has for its object to enable as large quantities as possible of macaroni to be subjected to drying in a very limited space, and yet the

drying to be carried out in an excellent manner, which is in no small degree assisted by the provision of large evaporating surfaces for the moisture contained in the macaroni. 50 For this object also the sections of passage for the air are enlarged and the entire drying operation is simplified. The latter result is attained by the macaroni being conveyed onto supports of absorbent material, similarly to what was the case in the method hereinbefore mentioned which supports are then stacked one above the other without further difficulty in the drying chamber, separate, inconvenient, means for covering, and the like, and also hurdles or stages and the like, being dispensed with.

55 By this invention the drying commences from the moment at which the macaroni is placed on the supports, a portion of the 75 moisture being immediately absorbed by the latter. Now before all the trays of macaroni have been arranged in the drying chamber, the supports will have absorbed a large 80 part of the moisture and in this way large evaporating surfaces are obtained, so that when air is passed over them, which may take place by artificial or natural means, the macaroni is rapidly freed from moisture. By the stacking of the macaroni and the supports one above the other the former is dried 85 extremely rapidly, as it is done internally and externally simultaneously. The supports may also be provided with longitudinal continuous passages and are then particularly adapted for drying thin and long macaroni, and also for that kind of macaroni that has no holes. Of course the macaroni and its supports may also be again arranged 90 in larger quantities in wood frames, but the same feature must always be maintained viz. that the macaroni on its absorbent supports is arranged in superimposed layers.

95 The method according to this invention will now be more particularly explained with 100 reference to an arrangement shown as an example in the accompanying drawings, in which:—

105 Figure 1 is a view of an apparatus for carrying out my method, while Figs. 2, 3 and 4 are end views of different forms and ways of placing the pasteboard or cardboard supports or trays one above the other.

110 The macaroni *b* passes out of the press *a* first onto a rocking frame *c* and onto supports or trays *e* of absorbent pasteboard, cardboard or the like, which are placed on

this rocking frame *c*. Preferably these trays *e* are provided with a bent up edge the height of which corresponds to the diameter of the macaroni. After the macaroni from the press *a* has been spread on the supports or trays *e* the rocking frame is moved upward horizontally in known manner, and the macaroni is thereby cut by a slicing device *d* to the correct lengths. The macaroni *b* is then brought into a drying apparatus *i*, the trays *e* being simply stacked one upon the other therein, so that macaroni and trays alternate through the entire pits. The trays *e* may also be provided in the middle with a bar *f* 15 or have longitudinal continuous passages *g*, so that the drying takes place more rapidly. The trays of macaroni, as shown in Fig. 3, may also be stacked in wooden frames *h*, without departing from the scope of the invention, whereby the macaroni is dried very rapidly.

In the form of construction shown in Fig. 4 the cardboard trays *e* are simply bent up at the ends.

I claim as my invention:—

The method of drying macaroni which consists in passing the macaroni directly from the press in a single layer on a tray of absorbent material, cutting the macaroni into suitable lengths, and then placing one tray 30 upon another so that the bottom of a superposed tray will contact with the macaroni in the tray directly underneath, whereby the layers of macaroni are brought into contact with the material from which the trays are 35 constructed.

In testimony whereof I affix my signature, in presence of two witnesses.

KARL GAMMEL.
